TREATING HYDROCARBON OILS

Harry H. Walker, Lockport, Ill., assignor, by
mesne assignments, to The Texas Company,
New York, N. Y., a corporation of Delaware

Application July 12, 1941, Serial No. 402,233

5 Claims. (Cl. 196—33)

This invention relates to a process of treating hydrocarbon oils, particularly petroleum oils, which results in freeing the oils of objectionable sulfur compounds such as mercaptans, which impart an undesirable odor to the oils.

The invention especially relates to an improved method of carrying out the so-called doctor treatment of sour hydrocarbon oils. In this treatment an alkaline solution of alkali metal plumbite, the doctor solution, is employed for contacting the sour oil, the solution usually being prepared by dissolving litharge in an aqueous solution of caustic soda. The treatment also usually comprises adding sulfur to the sour hydrocarbon oil, the sulfur being added either before or after the admixture of the sour oil with the doctor solution. In some cases the partially spent doctor may be removed from the oil prior to the addition of sulfur. Although it is now generally recognized that a number of side reaction occur simultaneously, the three main reactions considered to take place in this treatment are as follows:

In the above equations the letter R represents the hydrocarbon radical of a mercaptan present in the sour oil.

The final products of the treatment as shown by Equation 3 are disulfides and lead sulfide. The disulfides are oil-soluble, odorless compounds, which are retained in the finished oil. The lead sulfide, however, is insoluble in oil and must be removed. To this end the oil after treatment has been permitted to settle for an extended period of time to separate the lead sulfide. This has usually necessitated a large quantity of settling space. Also, it has been customary to subject the oil containing the lead sulfide to a washing with water, a time-consuming operation again requiring a settling period.

The present invention is concerned with an improvement which results in substantial increase in the rate and efficiency of the separation of suspended impurities, particularly lead sulfide, from a doctor-treated oil. It is also believed that the improvement may be employed with advantage in other situations where it is desired to 55

separate suspended impurities from hydrocarbon oils. For example, the invention can be applied to the separation of suspended lead sulfide from gasoline treated by a process in which an alkaline solution of lead sulfide is used.

It has been discovered in accordance with the invention that by injecting steam into a flowing stream of a hydrocarbon oil, such as gasoline or kerosene, following the doctor treatment of the oil, which oil therefore contains suspended lead sulfide and other impurities, the settling of these impurities is accelerated and made more complete. As a result the time of settling and equipment required therefor are reduced and the necessity for washing with water is eliminated.

To illustrate one manner in which the present invention may be applied, a conventional doctor treating process will be described. It will be understood that the invention may also be applied to other doctor treating processes which result in the production of a hydrocarbon oil containing suspended lead sulfide and other impurities. In the process in question, the sour oil is mixed with doctor solution by introducing the solution into a stream of the oil and then passing the combined materials through a conventional mixer. Sulfur, preferably in solution in oil, is then introduced in amount sufficient to convert the lead mercaptides, formed by reaction of mercaptans with sodium plumbite, to disulfides and lead sulfide. The resulting oil is then flowed through one or more settlers, which are usually enlarged chambers equipped with means for removing materials from the bottom and an overflow connection for carrying the oil, to remove excess doctor and the more easily precipitated lead sulfide and other impurities. The partially treated oil is then flowed in a confined stream to one or more final settlers, one or two plus a run-down tank usually being employed. It has been prior practice to subject the oil to a water wash prior to this introduction into the final settlers. This has required a relatively large quantity of water and also has caused a slowing-up of the operation in order to separate the water and obtain an oil of satisfactory color.

In applying the present invention to the system just described, the water wash is eliminated and while passing the confined stream of oil to the final settlers there is introduced a small amount of steam. This modified process is illustrated in the accompanying drawing, which represents a flow diagram of a preferred process for doctor treating and settling. It will be noted that the steam is introduced into the oil after the

substantial completion of the doctor treatment and it appears that the action of the steam is substantially entirely a physical action. By this procedure it has been found that the suspended impurities settle out rapidly, producing a clear product in a short time. As compared with a process using a water wash at the same charge rates the present process produces a product of substantially improved color without filtering.

It will be understood that the conditions of operation of a doctor treating process to which the present improvement is applied will not differ substantially from the conditions usually maintained. For example, in treating sour naphtha the temperature of the charge stock may vary from about 60° F. to 85° F. but in order to avoid emulsion difficulties it is generally preferred to operate within the range of 70° to 85° F. The pressure maintained during the operation will normally vary from atmospheric to about 15 pounds gauge. In doctor treating sour naphthas in the majority of refineries the naphtha charge rate will vary from 250 to 400 barrels per hour. As pointed out above, steam is introduced into a confined stream of the oil passing to the final settlers. At a charge rate within the above range, this stream may be carried by a line varying from about two inches to about six inches in internal diameter, and will usually have an internal diameter of three to four inches.

Under these conditions the steam may be introduced through a one-fourth inch to one-half inch line, and saturated live steam is ordinarily employed at a pressure above 100 pounds per square inch. Only enough steam is employed to effect complete dispersion of fine particles of water, since when using steam in excess no improvement in settling is noticed. It has been found that at naphtha charge rates as high as 400 barrels per hour a steam charge of two pounds per minute will accomplish the desired result and it may be stated that under these conditions a steam charge rate of greater than about three pounds per minute will be unnecessary.

In one operation of the process a sour naphtha charge rate of 330 barrels per hour was maintained and after completion of the doctor treatment and preliminary settling, saturated live steam at 140 pounds per square inch, approximately 95% quality, was introduced through a one-fourth inch line, the steam injection being at the rate of not more than one-half pound per barrel of naphtha charged. In this case the temperature was maintained at about 85° F. and the pressure from atmospheric pressure to 15 pounds gauge. As a result of the steam injection, the suspended lead sulfide appeared to coalesce so that an efficient separation was accomplished in the following settlers to yield a finished gasoline of good color.

When employing steam as described herein the rise in temperature of the confined stream of hydrocarbon oil is relatively small; for example, it rarely exceeds one or two degrees. In certain cases, particularly where the initial temperature of the oil is low, a greater rise in temperature, for example, a rise of 10 to 15° F. might result from the steam injection.

The reason why the injection of steam functions in the manner described is not clearly understood and it is therefore not intended to limit the invention to any theory of operation. However, it may be of advantage to point out that as usually practiced the injection of steam takes

place at a point in the system where the reaction is considered to have gone to completion and therefore the steam injection does not aid the actual chemical reaction taking place. Also, it appears that agitation alone is not the result of the injection because other kinds of agitation do not produce comparable results. One possible explanation is that the steam becomes dispersed in the naphtha in the form of small globules of water and, because of the great absorptive surface per unit quantity of water, is able to entrain suspended particles and cause their rapid precipitation and settling. There is also a possibility that the finely-dispersed water globules have an effect upon the electrical charge of the suspended particles of lead sulfide and by altering that charge increase the tendency of the lead sulfide particles to coalesce and form larger particles which settle rapidly.

20 The present invention is particularly important because of the continually growing understanding that in the doctor treatment of sour naphtha the use of an excess of sulfur should be avoided in order not to decrease the octane number or tetra-ethyl lead susceptibility of the finished gasoline. Where an excess of sulfur is used settling difficulties are reduced, but where only the amount of sulfur theoretically required is used, the lead sulfide is formed as finely divided particles which settle slowly under normal conditions. Thus, the present invention provides a means of producing rapidly a gasoline with exceptionally good characteristics with respect to sulfur content.

25 30 35 40 45 50 55 60 65 70 75

Obviously many modifications and variations of the invention, as hereinbefore set forth, may be made without departing from the spirit and scope thereof, and therefore only such limitations should be imposed as are indicated in the appended claims.

I claim:

1. In a process in which a confined stream of oil containing moisture and suspended lead sulfide flows through a settling vessel for the gravity separation of lead sulfide sludge, the method of improving the settling of said sludge which comprises introducing steam into said confined stream of oil and passing the resulting stream into said settling vessel.
2. In the process of sweetening a petroleum oil comprising treating an oil containing sulfur compounds with an alkaline solution of a lead compound to produce an oil substantially free from odiferous sulfur compounds but containing suspended lead sulfide, the improvement which comprises injecting steam into a confined flowing stream of the oil to increase the tendency of the suspended lead sulfide to precipitate, permitting the oil to settle, and separating precipitated lead sulfide from the oil.
3. In the process of sweetening a sour naphtha comprising mixing the naphtha with an alkaline solution of sodium plumbite, and also mixing the naphtha with an amount of sulfur at least sufficient to react with the lead mercaptides formed by the reaction of the mercaptans in said sour naphtha with said sodium plumbite, the improvement which comprises settling the naphtha after the addition of the alkaline solution of sodium plumbite and the sulfur to remove any excess of alkaline solution of sodium plumbite and the easily precipitated lead sulfide formed in the reaction, leaving a naphtha containing suspended lead sulfide, injecting steam into a confined flowing stream of said naphtha contain-

ing suspended lead sulfide to increase the tendency of said suspended lead sulfide to precipitate, and separating precipitated lead sulfide from the naphtha.

4. In the process of sweetening a sour naphtha comprising mixing the naphtha with an alkaline solution of sodium plumbite, and also mixing the naphtha with an amount of sulfur sufficient to react with the lead mercaptides formed by the reaction of the mercaptans in said sour naphtha with said sodium plumbite, the improvement which comprises settling the naphtha after addition of the alkaline solution of sodium plumbite and the sulfur to remove any excess of alkaline solution of sodium plumbite and the easily precipitated lead sulfide formed in the reaction, leaving a naphtha containing suspended lead sulfide, injecting steam into a confined flowing stream of said naphtha containing suspended lead sulfide to increase the tendency of said suspended lead sulfide to precipitate, the steam being injected in an amount corresponding to about one-half pound of steam for each barrel of naphtha, and separating precipitated lead sulfide from the naphtha.

5. In the process of sweetening a sour naphtha

comprising mixing the naphtha with an alkaline solution of sodium plumbite, and also mixing the naphtha with an amount of sulfur sufficient to react with the lead mercaptides formed by the reaction of the mercaptans in said sour naphtha with said sodium plumbite, the improvement which comprises settling the naphtha after addition of the alkaline solution of sodium plumbite and the sulfur to remove any excess of alkaline solution of sodium plumbite and the easily precipitated lead sulfide formed in the reaction, leaving a naphtha containing suspended lead sulfide, flowing said naphtha containing suspended lead sulfide in a confined stream, injecting steam into said confined stream to increase the tendency of the suspended lead sulfide to precipitate, the amount of steam injected corresponding to not more than three pounds per minute through a line having an internal diameter of about one-fourth to one-half inch for a naphtha flow of about 250 to 400 barrels per hour through a line having an internal diameter of about two to six inches, and separating precipitated lead sulfide from the naphtha.
